his Atts.

UNITED STATES PATENT OFFICE.

SAMUEL J. BALLARD, OF LOS ANGELES, CALIFORNIA, ASSIGNOR OF THREE-FOURTHS TO CALVIN W. BROWN, OF LOS ANGELES, CALIFORNIA.

GUARD FOR SPEECH RECEIVERS AND TRANSMITTERS.

SPECIFICATION forming part of Letters Patent No. 732,915, dated July 7, 1903.

Application filed October 14, 1902. Serial No. 127,293. (No model.)

To all whom it may concern:

Be it known that I, SAMUEL J. BALLARD, a citizen of the United States, residing at Los Angeles, in the county of Los Angeles and 5 State of California, have invented a new and useful Guard for Speech Receivers and Transmitters, of which the following is a specification.

This invention relates to the device described and claimed in my application for Letters Patent of the United States filed July 2, 1901, Serial No. 66,921, and has for its object the further improvement of the device therein disclosed.

15 To these ends my invention consists in the constructions, devices, and combinations of parts hereinafter described, and particularly pointed out in the claims, and will be more readily understood by reference to the accompanying drawings, forming part of this specification, in which—

Figure I is a perspective view of the invention with the protecting leaves, slips, or sheets and in use as an attachment to a telephone-transmitter. Fig. II shows the device in use on a telephone-receiver. Fig. III is a perspective view of the device ready for attachment to a transmitter or receiver. Fig. IV is a side view. Fig. V is a perspective view of 25 a device embodying my invention attached to a telephone-transmitter. Fig. VI is a fragmental sectional view. Fig. VII is a front view of the blank from which the frame is constructed.

30 1 indicates a plurality of protecting slips or sheets of paper or any other suitable material. Paper of any desired thickness may be used, as I have found by experiment that two sheets of thick blotting-paper will not prevent the ready transmission and reception of sound through the telephone. 2 indicates in a general way a holder for said sheets adapted and arranged to hold said sheets or slips in position for being respectively and successively moved into position in front of the instrument to which it is adjusted. In practice the outside slip or sheet *a* or the one next thereto can be turned into position across the mouth of the instrument, as indicated in Figs. I, III, 45 and V.

3 indicates the transmitting or receiving

appliance, to which the holder will be attached by a clamp 4. The holder comprises a standard 5, connected with the clamp 4, and a guide 6, fastened to the standard to guide the edges 55 of the leaves or slips 1.

7 indicates a leaf-supporter, as a post or pin, extending alongside the guide at a distance therefrom to pass through perforations 8 in the protecting slips or sheets. A plate 9 is 60 provided with an opening near its lower edge and an inwardly-extending sleeve 10, adapted to slip over the supporter 7. The plate is thus adapted to slide on the supporter 7. I provide a retainer 11 for the outer end of the 65 supporter 7. This retainer may be of any desired form. In order to insure the ready turning of the several sheets *a* on the supporter, I provide a loose washer 12 on the supporter 7 between the front sheet *a* and the retainer 11. As a sheet *a* is turned on the supporter 7 this washer readily turns with it, insuring its ready movement and preventing its tearing. An arm 20 is carried up from the standard 5 and bent forward over the top of 70 the plate 9, its end being bent down, so as to adapt it to hold the slips or sheets of paper against the plate 9 in a smooth pad or block. Projections 21 and 22 are provided opposite each other on the standard 5 and inside the 75 plate 9, respectively, and a coiled spring 13, mounted thereon. This spring provides resilient means whereby the plate 9 is pressed outward on the bar 7.

The clamp 4, standard 5, and guide 6 are 80 preferably all formed of a single piece of bent sheet metal. 14 in a general way indicates a blank from which said parts will be pressed into shape.

15 indicates a clamp bolt and nut for clamping the frame on the earpiece or mouthpiece. An arm 23 is pivoted on the bolt 15 and extends out therefrom, having its outer end bent up, as shown, as a support for the sheet *a* when the same is brought over the mouth or 90 ear piece.

In practical use the appliance will be fastened to the telephone or other mouthpiece or earpiece, and a bunch of slips perforated with a hole 8 will be placed on the guides 6 100 and over the pin 7 and will be secured by a suitable retainer, such as that shown at 11,

the spring 13 being compressed to admit of the insertion of the sheets between the plate 9 and the retainer 11. The pressure of the spring 13 constantly holds the sheets forward in position against the retainer, and the user, whenever he desires, may turn a sheet to bring it past the ends of the guide 6, which for this purpose terminate rearward of the end of the bar or pin 7. When the sheet is turned into position across the opening of the receiver or transmitter, the appliance is ready for use. It is to be understood that the slips *a* may be wholly or partially given over to advertising, or advertisements may be omitted, at the pleasure of the user, without departing from the broad spirit of my invention. When the user desires to provide a new surface, he will tear off the old slip and turn a new slip into place.

20 16 indicates a cross-bar formed of the sheet from which the members 4 4, 5, and 6 6 are bent.

17 indicates the hole in the standard 5 for fastening the pin 7 to said standard.

25 In bending the frame comprising the cross-bar 16, clamp members 4, standard 5, and guide members 6 the clamp members 4 will first be bent forward at the dotted lines *x* and then at the dotted lines *y*. The members 30 6 will be bent forward at the dotted lines *z*, thus leaving the bar 16 and the standard 5 at one edge of the bar in one common plane, the guide-arms 6 projecting forward lengthwise from the bar at the edge thereof from which 35 the standard projects and the clamp-arms 4 projecting edgewise from the bar opposite the guide-arms.

The designating number of the telephone to which the device is applied may be stamped 40 on or otherwise applied to the face of the retainer, thus to inform the user of the telephone as to the number thereof.

It is obvious that my device is equally adapted for use on a transmitter or receiver, and I 45 use either term as including the other.

The inwardly-extending sleeve or hub 10 not only serves to prevent the binding of the plate upon the pin or supporter 7, but also serves as means to prevent the plate 10 tilting 50 or tipping upon the supporter, while the members 6 not only serve as guides for the edges of the leaves or slips, but as means to prevent the plate revolving upon the supporter. It is thus seen that the inwardly-extending sleeve 55 or hub 10 has a double function.

Having described my invention, what I claim, and desire to secure by Letters Patent of the United States, is—

1. The combination, of the holding-frame 60 provided with a clamp and a projecting pin, of a plate slidably arranged thereon, a retainer on said pin, and means for pressing leaves toward said retainer.

2. The combination, of a holder-frame pro- 65 vided with a clamp and a projecting pin, of a plate slidably arranged thereon, a retainer on said pin, means for pressing leaves toward

said retainer, and an arm or holder adapted to hold leaves against said plate.

3. The combination, of a holder-frame, pro- 70 vided with a clamp and a projecting pin, a retainer thereon, means for pressing leaves toward said retainer, and revoluble means in connection with said retainer adapted to turn as a leaf is turned on said pin.

4. The combination, with the holder-frame provided with a clamp and a projecting pin, of a plate slidably arranged thereon, a retainer, revoluble means between said plate and retainer, and yielding means adapted to 80 carry said plate toward said retainer.

5. The combination, with the holder-frame provided with a clamp and a projecting pin, of a plate slidably arranged thereon, a retainer, revoluble means between said plate and retainer, yielding means adapted to carry 85 said plate toward said retainer, and means adapted to hold leaves or strips against said plate.

6. The combination, with the holder-frame 90 provided with a clamp and a projecting pin, of a plate slidably arranged thereon, a retainer, revoluble means between said plate and retainer, yielding means adapted to carry said plate toward said retainer, means adapted 95 to hold leaves or strips against said plate, and means adapted to support a leaf in position in front of the receiver.

7. A leaf-holder for speech receivers and transmitters comprising a base, a leaf-supporter projecting therefrom, a guide below the supporter extending parallel therewith, a retainer on the outer end of the supporter beyond the end of said guide, means for carrying forward leaves upon said guide, revoluble 105 means on said pin between said retainer and the leaves, and auxiliary means for supporting the leaf.

8. The combination, of the holder-frame, provided with a clamp and a projecting pin, 110 a plate slidably arranged thereon, a retainer, revoluble means on said pin between said plate and retainer, a spring between said frame and plate, and an arm projecting from said frame up over said plate, provided with 115 a depending portion, adapted to hold the leaves against said plate.

9. The combination with a transmitter, of the holder-frame, provided with a clamp and a projecting pin, a plate slidably arranged 120 thereon, a retainer, revoluble means on said pin between said plate and retainer, a spring between said frame and plate, and an arm depending from said frame and adapted to hold a leaf in position over the transmitter.

10. The combination with a transmitter, of the holder-frame, provided with a clamp and a projecting pin, a plate slidably arranged 125 thereon, a retainer, revoluble means on said pin between said plate and retainer, a spring between said frame and plate, and an arm projecting from said frame up over said plate, provided with a depending portion, adapted to hold leaves against said plate, and an arm 130

depending from said frame and adapted to hold a leaf in position over the transmitter.

11. The combination, of the holder-frame, provided with a clamp and a projecting pin and parallel bars, of a plate slidably arranged on said pin, a retainer adapted to hold leaves on said pin, and an arm projecting from said frame over the edge of said plate and adapted to support the leaves against said plate.

12. The combination, with the frame-holder, provided with a clamp and a projecting pin, a plate slidably arranged thereon, means for preventing the binding of said plate on said pin, a retainer, and means for pressing leaves toward said retainer.

13. The combination, with the frame-holder, provided with a clamp and a projecting pin, a plate slidably arranged thereon, means for preventing the tilting or tipping of said plate, means for preventing the binding of said plate on said pin, a retainer, and means for pressing leaves toward said retainer.

14. The combination, with a base, provided with a clamp and a projecting pin, of a plate slidably arranged thereon, means for preventing the tilting or tipping of said plate, a re-

tainer, and means for pressing the plate toward said retainer.

15. The combination, of the holder-frame provided with a clamp and a projecting pin and parallel bars, of a plate slidably arranged on said pin, means for preventing the tilting or tipping of said plate, a retainer adapted to hold leaves on said pin, and an arm projecting from said pin over the edge of said plate and adapted to support the leaves against said plate.

16. The combination with a base provided with a clamp and a projecting pin, of a plate slidably arranged thereon, means for preventing the plate revolving on said pin, a retainer, and means for pressing said plate toward said retainer.

In testimony whereof I have signed my name to this specification, in the presence of two subscribing witnesses, at Los Angeles, in the county of Los Angeles and State of California, this 8th day of October, 1902.

SAMUEL J. BALLARD.
